INTERRUPTER FOR ROTARY PRINTING
MACHINES

Frank Sydney Thompson, Cheadle Hulme, England, assignor to T. C. Thompson & Son Limited, Manchester, England, a corporation of Great Britain

Filed Sept. 29, 1962, Ser. No. 225,106

Claims priority, application Great Britain Sept. 21, 1961
 1 Claim. (Cl. 101—247)

This invention relates to rotary printing machines of the type in which a plate cylinder is mounted to swing into and out of engagement with a stationary impression cylinder which feeds sheets for printing between the nip of the two cylinders.

It has been proposed in a machine having a plate cylinder carrying soft letterpress moulded in relief on a rubber or other resilient sheet to stand proud of the surface to mount the plate cylinder on a frame pivoted about the axis of an inking drum to be capable of being moved into and out of contact with the impression cylinder whilst remaining in contact with the inking drum.

Such an arrangement cannot be employed with thin hard letterpress printing plates curved around and mounted on the plate cylinder and having the raised letterpress etched out of the printing plate due to the more complicated inking mechanism requiring soft inking rollers interposed between the drum and the type and the object of the present invention is to provide a swinging unit for use with such machines.

According to the invention the plate cylinder and inking rollers are mounted in a frame pivoted on the axis of an inking drum, means being provided to swing the frame into and out of engagement with a stationary impression cylinder without disturbing the setting of the plate cylinder and rollers.

The invention will be described with reference to the accompanying drawings:

FIG. 1 is a diagrammatic side elevation of the ink supply rollers to the plate cylinder C¹ mounted on the frame B and showing the plate in contact with the impression cylinder C, the mountings for the inking rollers b, b¹ and the cam D¹ being omitted for clearness.

FIG. 2 is an enlarged elevation showing the inking rollers b, b¹ and cam D¹ mounted on the frame B.

FIG. 3 is a vertical section showing the mounting of the frame and plate cylinder and inking rollers.

The printing machine A is provided with an ink duct a and feed rollers a¹ for supplying ink to an ink drum A¹ in which ink is taken up by a roller a¹⁰ from the duct a and transferred to a vibrating roller a¹¹ which intermittently delivers the ink to the first feed roller a¹² and through the train of rollers a¹. The cylinders and feed rollers may also be driven in known manner.

The ink drum A¹ is mounted on the shaft a² to rotate in the main frame A of the machine and an impression cylinder C and sheet feeding mechanism c¹ therefor are also mounted in the main frame A.

The impression cylinder C is mounted to rotate about a fixed axis in the machine frame so that the relationship between it and the feed and delivery mechanism need not be disturbed.

A plate cylinder C¹ carries a thin plate (of the order of 0.025 inch thick with the letterpress or the like etched or otherwise formed thereon about 0.010 inch deep) curved around the periphery of the cylinder and secured to the cylinder in known manner. The plate cylinder C¹ is mounted on a concentric shaft c rotatably mounted in a frame B pivoted on the shaft a² on which the ink drum A¹ is mounted. The impression cylinder C is connected to the plate cylinder C¹ by an arm C² at each end of the cylinder, each arm engaging an eccentric portion C of the

shaft c upon which the plate cylinder C¹ is mounted, rotation of the shaft c bringing the plate cylinder C¹ into or out of contact with the impression cylinder C as shown in chain dotted lines in FIG. 1.

The frame B may be rocked about the shaft a² from the position shown in FIG. 1 to the chain dotted position to bring the plate cylinder C¹ into or out of engagement with the impression cylinder C by a lever D mounted on a spindle d carried in the machine frame A, through an arm d¹ also mounted on the spindle d and provided with a roller d² engaging a slot in a forked bracket b² mounted on the shaft c about which the plate cylinder C¹ rotates. The bearings for the shaft c in the arms C² are eccentric with respect to the plate cylinder C¹ whereby movement of the lever D from the position shown in FIG. 1 in the direction of the arrows brings the plate cylinder C¹ out of engagement with the impression cylinder C by rotating the eccentric shaft c. The lever D when in the position shown in FIG. 1 exerts pressure between the plate cylinder C¹ and the impression cylinder C to retain the two cylinders in contact.

In order to adjust the pressure and alignment between the plate cylinder C¹ and the impression cylinder C this latter is mounted on a shaft c² and provided with an eccentric bush c³ at each end. The bushes c³ are provided with teeth on a portion of their periphery engaged by worm wheels c⁴ rotation which displaces the levers C² and consequently the frame B to vary the distance between the axes of the shafts c, c² when the cylinders are in contact and thus the pressure exerted therebetween and allow for correction of the alignment of the cylinder.

Two or more inking rollers b, b¹ for transferring ink from the ink drum A¹ to the plate cylinder C¹ are mounted on the frame B to move therewith about the shaft a² and thus the plate cylinder C¹ may be brought into or out of engagement with the impression cylinder C or adjusted for pressure without disturbing the settings of the rollers b, b¹.

The ink rollers b, b¹ may be of a circumference equal to the longest sheet to be printed, thus obviating repeats and may be mounted on the independent frame B in bearing recesses in levers b³, b³¹ to swing tangentially to the surface of the ink drum A¹.

When the plate cylinder C¹ is brought out of engagement with the impression cylinder C it may be desirable to also interrupt the inking of the plate cylinder by lifting the inking rollers b, b¹ out of engagement therewith or in addition to interrupt the supply of ink to the first feed roller a¹².

A three armed cam D¹ is pivoted on the frame B having two cam surfaces d³, d³¹ to engage respectively the levers b³, b³¹ as the cam D is rotated from position 1 in FIG. 2 to position 2 (shown chain dotted) by a lever D² to lift the arms b³, b³¹ to bring the inking rollers b, b¹ out of contact with the plate cylinder C¹.

In order to interrupt the supply of ink to the vibrating roller a¹¹ one end of a rod a⁴ is pivoted to the third arm of the cam D¹ the other end being pivoted to a pivoted link a⁵ on the frame A movement of the lever D² bringing the link a⁵ into engagement with a rod a⁶ depending from a cradle carrying the vibrating roller a¹¹ to arrest the movement of the cradle. The initial movement of the cam D¹ from position 1 to position 2 does not bring the link a⁵ into engagement with the rod a⁶ and the movement of the cam D¹ from position 2 to position 3 does not affect the movement of the rollers b, b¹ as a radial portion of the cam surfaces d³, d³¹ engages the levers b³, b³¹.

The pressure between the inking rollers b, b¹ and the drum A¹ is adjusted by pivoting the levers b³, b³¹ on eccentric fulcrum pins b³² rotation of which by levers b³³

raises or lowers the rollers b , b^1 . Adjustment of the pressure between the rollers b , b^1 and the plate cylinder C^1 is obtained through pins b^6 engaging the inner surface of each lever b^3 , b^{31} . The pins b^6 are also eccentric so that rotation by levers b^{31} against the action of springs b^{62} causes the levers b^3 , b^{31} to move transversely.

The eccentric fulcrum pins b^{32} are locked in position against the plate B by nuts b^{35} screwed thereon. Further nuts b^{34} screwed onto the pins b^6 lock these pins to the plate B . The levers b^3 , b^{31} may be rocked to bring the rollers b , b^1 clear of both the inking drum A^1 and the plate cylinder C^1 for removal by pins b^{51} on a pivoted shaft b^{52} actuated by a control arm b^5 to cause the pins b^{51} to engage the tail ends b^4 of the levers.

I claim:

A rotary printing machine comprising a support, an impression cylinder mounted for rotation about its axis on said support, an inking drum mounted for rotation on its axis on said support, a frame pivoted on said support for displacement about the axis of said inking drum, a plate cylinder adapted to have a printing surface thereon provided with oppositely extending concentric shafts extending rotatably through said frame, spaced rigid arms each rockably mounted on said support at one end and pivotally mounting said shafts at the other end, the rockable mounting of said one end of said arms being eccentric to the axis of said impression cylinder and said

10
15

plate cylinder in printing position being disposed in printing engagement with said impression cylinder to define a nip through which pass the sheets to be printed, means for adjusting said eccentric mounting to vary the printing engagement pressure between the impression and plate cylinders, a plurality of inking rollers mounted for rotation on said frame about their axes and normally having peripheral ink transfer contact with both said inking drum and said plate cylinder, and cooperating means on said frame and said arms adjustable for swinging said frame about the axis of said inking drum for displacing said plate cylinder out of printing engagement with said impression cylinder while maintaining said inking rollers in engagement with both said inking drum and said plate cylinder.
